UNITED STATES PATENT OFFICE.

EDWARD F. GOODWIN, OF TAUNTON, MASSACHUSETTS.

SHUTTER-WORKER.

SPECIFICATION forming part of Letters Patent No. 375,151, dated December 20, 1887.

Application filed August 1, 1887. Serial No. 245,790. (No model.)

To all whom it may concern:

Be it known that I, EDWARD F. GOODWIN, a citizen of the United States, residing at Taunton, in the county of Bristol and Commonwealth of Massachusetts, have invented 5 certain new and useful Improvements in Blind-Operators, of which the following is a full, clear, and exact specification.

My invention relates to improvements in 10 blind-operators, whereby the blind may be opened or closed and the blind-slats, by the action of an eccentric, raised or lowered from the inside without opening the window.

Figure 1 of the accompanying drawings represents a side elevation of the device, the blind 15 being in a perpendicular position relative to the window-frame. Fig. 2 is a front elevation in a direction at right angles to the first, the blind being in the same relative position as 20 before. Fig. 3 is a plan view of the same; Fig. 4, an end view of the handles as they would appear from the inside. Figs. 5 and 6 represent parts of the device for operating the 25 slats. Fig. 7 is a view of the ratchet R and the detent M, the handle E being cut off.

A A is the frame of the blind; H, the part of 30 the lower hinge attached to the wall or window-frame, and H' the corresponding part attached to the blind.

B' is a bevel-gear forming an integral part 35 of the portion of the hinge H', the axis of the wheel B' being in the same vertical line as the axis of the pin h, on which the hinge turns. B' works with the corresponding bevel-gear, B, which is connected, by the hollow spindle G, to the handle or bevel-knob E on the inner side of the frame or wall. Inside the hollow spindle G is fitted loosely a smaller solid spindle, F, provided at its inner end with a handle, D. This spindle G passes through a hole made 40 in the center of the bevel-gear B and is eccentrically attached at N to the face of the circular disk C.

P is a frame in which the eccentric C turns, 45 K K' being vertical guide-rods attached, respectively, to the top and bottom of the frame P, the lower rod, K', playing up and down

through a hole in the center of the bevel-gear B', and the upper rod, K, passing through a hole in the center of the pin h of the lower 50 blind-hinge. The upper end of the rod K is attached in any suitable way to one end of the lever L, which is pivoted at S, so as to turn freely, the other end of the lever being attached loosely by means of the ring T, or in 55 any other suitable manner, to one end of the blind-slats, as shown.

By turning the larger knob, E, the blind may be opened or closed, suitable means—as by a detent, M, and a ratchet or toothed wheel, R— 60 being employed to retain the blind in any desired position.

The detent M is raised by the fingers while the blind is being moved and shut down when the blind is in the desired position. 65

By turning the knob D the frame P is raised or lowered through the eccentric or cam C, which, by means of the rod K and lever L, operates the blind-slats to close or open them. 70

What I claim is—

1. A blind-operator consisting of a hollow spindle provided with a handle and suitable means for preventing it from turning, attached to a bevel-gear which works with a corresponding gear attached to and forming an integral part of the portion of the hinge mounted on the blind, in combination with a solid spindle passing through the hollow spindle, an eccentric turning in a frame, and a connecting-lever attached to the blind-slats, all arranged 75 and operated substantially as set forth.

2. In a blind-operator, the combination of a spindle operating an eccentric, a frame provided with vertical guide-rods, one of which passes through the hollow pin of the portion 80 of the hinge mounted on the wall or window-frame, and a lever attached to the blind-slats, substantially as described.

In witness whereof I have hereunto set my hand.

EDWARD F. GOODWIN.
